FACE PLATE FOR A PHOTOGRAPHIC CAMERA OR SIMILAR ARTICLE

Andrew V. McClare, Rochester, N.Y., assignor to Eastman Kodak Company, Rochester, N.Y., a corporation of New Jersey

Filed Dec. 26, 1967, Ser. No. 9,921

Term of patent 14 years

(Cl. D61—1)

FIG.2

FIG.5

FIG.1

FIG.4

FIG.3

FIG.9

FIG.6

FIG.8

FIG.7

FIG. 1 is a front elevational view of a face plate for a photographic camera or similar article showing a first embodiment of my novel design wherein one substantially square figure appears near a circular figure;

FIG. 2 is a top plan view of the embodiment shown in FIG. 1;

FIG. 3 is a bottom plan view of the embodiment shown in FIG. 1;

FIG. 4 is a left-side elevational view of the embodiment shown in FIG. 1;

FIG. 5 is a right-side elevational view of the embodiment shown in FIG. 1;

FIG. 6 is a front elevational view of a face plate for a photographic camera or similar article, showing a second embodiment of my novel design wherein two substantially square figures appear near a circular figure;

FIG. 7 is a bottom plan view of the embodiment shown in FIG. 6;

FIG. 8 is a left-side elevational view of the embodiment shown in FIG. 6;

FIG. 9 is a right-side elevational view of the embodiment shown in FIG. 6;

The broken-line fragmentary showing, in FIGS. 1—9, of the front portion of a photographic camera or similar article with which the face plate of my novel design may be associated is for illustrative purposes only.

I claim:

The ornamental design for a face plate for a photographic camera or similar article, as shown and described.
